UNITED STATES PATENT OFFICE.

JULES H. VENON, OF NEW YORK, N. Y.

DESIGN FOR A GOBLET OR SIMILAR ARTICLE.

Application filed January 6, 1927. Serial No. 20,294. Term of patent 14 years.

To all whom it may concern:

Be it known that I, JULES H. VENON, a citizen of the United States, and resident of the city, county, and State of New York, have invented a new, original, and ornamental Design for a Goblet or Similar Article, of which the following is a specification, reference being had to the accompanying drawing, forming part thereof.

In the drawing is shown, in elevation, a goblet showing my new design.

The important feature of the design is the configuration of the top part of the article.

I claim:—

The ornamental design for a goblet or similar article, as shown and described.

JULES H. VENON.
